UNITED STATES PATENT OFFICE.

JOHN J. CUSICK, OF NEW YORK, N. Y.

MAIL CHUTE.

Application filed July 12, 1922. Serial No. 574,421.

To all whom it may concern:

Be it known that I, JOHN J. CUSICK, a citizen of the United States, and a resident of the city of New York, borough of Manhattan, in the county and State of New York, have invented a new and Improved Mail Chute, of which the following is a description.

My invention relates to mail chutes and particularly to the mail chutes provided in office buildings and apartment houses and having letter drops at the various floors of the building.

In the actual use of the mail chutes referred to, it not infrequently occurs that the chute becomes clogged by the forcing of mail matter into the drop of a size or character that will cause it to become wedged in the chute. For example, bulky letters or packages are doubled or otherwise bent and compressed into a sufficiently small compass to enter the slot or opening of the letter drop so that deposited matter will expand and wedge itself in the chute. A further objectionable feature of the usual chute is that the clogged matter is not readily accessible.

The general object of my invention is to provide in association with the letter drop of each floor an auxiliary choke chute which will retain any matter deposited therein which could possibly clog the main chute.

A further object of the invention is to provide means to afford ready access to the choke chute should it become clogged, and to provide means for locking the said first means so that unauthorized persons may not gain access to the auxiliary chute.

The means by which the above and other objects are attained and the advantages of the invention will more clearly appear as the invention proceeds.

Reference is to be had to the accompanying drawing, it being understood that the drawing is merely illustrative of two examples of the invention.

Figure 1 is a perspective view of a mail chute embodying my invention;

Figure 2 is a transverse vertical section;

Figure 3 is a longitudinal vertical section through the top of the auxiliary chute forming the letter drop; and

Figure 4 is a detail and transverse vertical section illustrating a modification.

In the illustrated example the numeral 10 indicates a mail chute adapted in practice to extend vertically in a building. At each floor of the building I provide in association with the main chute 10 an auxiliary choke chute 11, the front of which for its major portion is parallel with the main chute. The lower portion 12 of the auxiliary chute extends obliquely from the vertical front portion toward the main chute and merges into the front wall 13 of the main chute. Said front wall 13 is broken at the inclined portion 12 so that the main and auxiliary chutes are in communication. The obliquity of the lower portion 12 of the auxiliary chute 11 to the plane of the front wall 13 of the main chute results in a choke 14 at the lower end of the auxiliary chute 11. The auxiliary chute 11 has parallel vertical walls for its major portion. The front vertical wall is provided with a glass panel 15, the lower end of which sets, in the present instance, behind a frame element or transverse cleat 16. The side edges of the glass panel 15 are slidably fitted in groove 17 in the sides of the auxiliary chute 11 so that said glass panel may be lifted and removed for affording access to the auxiliary chute should the latter become choked. The auxiliary chute 11 above the choke 14 is of larger cross sectional area than the main chute 10 to thus constitute an expansion chamber for folded or squeezed mail matter.

I provide for locking the removable glass panel 15, for which purpose in the form shown in Figures 1 to 3, a letter drop is afforded through an opening 18 in a top board 19 on the chute 11. Said board 19 at one end (see Figure 3) is adapted to be entered in a notch 20 in one side wall of the auxiliary chute 11 and the board has a sufficient width to overlie the top of the glass panel 15, there being a notch 21 in the underside of the board 19 to receive the upper edge of the panel 15. On the board 19 at the underside is a lock 22 at that end of the board opposite the notch 20, and the latch bolt 23 of the lock is adapted to be operated by a key inserted in a key-hole 24 in the board 19. It will

be understood that any suitable plate or closure may be employed for the top of the chute 11 and affording a letter drop.

By my described arrangement, if a bulky letter or other like package is forced through the drop opening 18 so that it will expand to a size and form that would choke the main chute 10, the said letter will assume its enlarged form in the parallel portion of the chute 11 with the probability of wedging itself in said parallel portion. At all events the choke 14 will not pass any mailed letter or other article of a size and form to choke the main chute 10. Should the auxiliary chute 11 become clogged the closure 19 may be readily removed and this will permit the removal of the panel 15 for the ready clearing of the chute. The removal of the panel 15 will not automatically dislodge matter wedged in the choke 14, or permit its escape through the main chute, the removable panel 15 being above the choke 14.

In Figure 4 the cover 119 for the top of the auxiliary chute 111 is provided with a lock 122 and with a notch 121 to engage the upper edge of the removable glass panel 115. The cover 119 is hinged at its rear edge as at 120 to be raised or lowered for releasing or engaging the panel 115. When the panel 115 is disengaged from the cover 119, said panel may be removed by sliding it vertically in the groove 117. In the form of the invention illustrated, the panel 115 has an opening 118 for use as a letter drop and in order to prevent a person using an instrument with a view to force downwardly any matter observed to wedge in the auxiliary chute 111, I provide a guard 124 at the inner side of the panel 115.

I would state in conclusion that although the illustrated form constitutes a practical embodiment of my invention I do not wish to be understood as limiting myself to the precise details illustrated, since manifestly, the same can be considerably varied without departing from the spirit of the invention as defined in the appended claims.

I claim:

- 50 1. A mail chute comprising a main chute and an auxiliary chute affording an entrance for matter to be mailed and communicating at its lower end with the main chute, said lower end of the auxiliary chute constituting a choke to exclude from the main chute matter that would clog the latter, said auxiliary chute above said choke being of greater cross sectional area than the main chute and having a removable panel above said choke.
- 60 2. A mail chute comprising a main chute and an auxiliary chute affording an entrance for matter to be mailed and communicating at its lower end with the main chute, said lower end of the auxiliary chute constituting a choke to exclude from the main

chute matter that would clog the latter, said auxiliary chute being of approximately uniform width for its major portion above said choke and said major portion being of greater cross sectional area than the main chute to permit greater expansion of mail matter than the main chute.

3. A mail chute including a main chute and an auxiliary chute affording an opening for entrance of mail and communicating at its lower end with the main chute, the major portion of the auxiliary chute being of approximately uniform width, said auxiliary chute having a removable vertically slideable panel at said portion of uniform width, and the auxiliary chute below said panel forming a choke to exclude from the main chute matter that would clog the same.

4. A mail chute including a main chute, an auxiliary chute, the lower portion of which forms a choke to exclude matter that would clog the main chute, said auxiliary chute presenting grooves in opposite sides, a vertically slideable panel fitting said grooves, and a movable closure for the outer end of the auxiliary chute, said closure adapted to be engaged with or to disengage said panel to retain the panel or to permit removal thereof.

5. A mail chute including a main chute, an auxiliary chute, the lower portion of which forms a choke to exclude matter that would clog the main chute, said auxiliary chute presenting vertical grooves in opposite sides, a panel slidably fitting said grooves, and a movable closure for the outer end of the auxiliary chute, said closure adapted to be engaged with or to disengage said panel to retain the panel or to permit removal thereof; together with means to lock said closure in position.

6. In a mail chute, a main chute, an auxiliary chute having a transparent front wall extending substantially parallel with the walls of the main chute and an inclined wall extending at an angle to said transparent wall connecting said wall with the front wall of the main chute.

7. In a mail chute, the combination with a main chute of an auxiliary chute arranged in the front of the main chute and provided with a wall substantially parallel with the front wall of the main chute and a second wall extending at an angle to said parallel walls and connecting the front wall of the auxiliary chute with the front wall of the main chute, the front wall of the main chute being open adjacent the upper portion of said second wall for affording a communication of the auxiliary chute with the main chute.

8. In combination with a main chute, of an auxiliary chute having side walls presenting vertically extending grooves at their

- inner faces adapted to receive a transparent panel and a key-operated slotted cover provided with an under slotted groove adapted to engage the upper end of said panel.
- 5 9. A mail chute including a main chute and an auxiliary chute, the lower portion of the auxiliary chute forming a choking chamber to exclude matter that would clog the main chute, said auxiliary chute presenting grooves in the inner faces of its sides, a vertically-slidable panel fitting the said grooves and a movable closure formed with a slot at its under face adapted to receive the upper end of said panel to retain the upper end of said panel in position.

JOHN J. CUSICK.
